UNITED STATES PATENT OFFICE.

WILLIAM L. McGOWAN, OF GALT, MISSOURI.

IRONING BOARD.

Application filed October 8, 1924. Serial No. 742,398.

- The invention relates to ironing boards, and has for its object to provide a device of this character of the wall type wherein a board is disposed within the frame imbedded 5 in the wall and the board carried by a vertically movable carriage, which carriage is held in various adjusted positions by pivoted levers, with which the inner end of the hinged ironing board cooperates. Also to 10 provide counterweights for the carriage whereby the weight of the carriage is partially supported thereby allowing the carriage to be easily moved to a desired elevation. 15 A further object is to provide the opposite sides of the inner end of the ironing board with cutaway portions which receive the upper ends of the side rails of the carriage when the board is folded into the casing, 20 thereby allowing the use of an ironing board of a maximum width. Also to provide the upper ends of the side bars of the carriage with spring actuated ball detents cooperating with the ironing board for holding said 25 ironing board in a vertical position, for storage purposes.
- A further object is to hingedly connect to the upper end of the carriage a sleeve board, which sleeve board is held in a horizontal 30 position by means of a bracing leg hinged to the underside of the board and adapted to engage the carriage, and to provide said leg with an aperture positioned whereby when the sleeve board is in a vertical inoperative position, said aperture will receive a headed lug or screw carried by the carriage and maintain the sleeve board in vertical position. 35
- With the above and other objects in view 40 the invention resides in the combination and arrangement of parts as hereinafter set forth, shown in the drawing, described and claimed, it being understood that changes in the precise embodiment of the invention may 45 be made within the scope of what is claimed without departing from the spirit of the invention.
- In the drawing:—
- Figure 1 is a front elevation of the cabinet 50 ironing board.
- Figure 2 is a vertical transverse sectional view through the lower end of the cabinet and through the ironing board carrier, showing the ironing boards in horizontal position. 55
- Figure 3 is an enlarged front elevation of one side of the carriage, parts being shown broken away to better show the structure. 60
- Figure 4 is a horizontal sectional view taken on line 4—4 of Figure 2.
- Referring to the drawing, the numeral 1 designates the casing of the wall cabinet, which is imbedded in the wall 2 and is vertically disposed. The casing 1 is provided with a chamber 3, in which the mechanism and ironing boards hereinafter set forth are 65 disposed. If desired a closure may be provided for the cabinet, however the closure or door has been eliminated in the drawing to more clearly illustrate the device. Disposed within the chamber 3 and vertically 70 slidable on oppositely disposed guide strips 4 is a carriage 5. The carriage 5 comprises vertically disposed side bars 6, in the channels 7 of which the guide strips 4 are received, and which bars 6 have their forward 75 sides connected together by a horizontally disposed bar 8 and their rear sides connected by the relatively wide bar 9 which is located above the bar 8 a distance equal to the thickness of the ironing board 10 whereby when 80 said ironing board is moved to a horizontal position on its hinging point 11, as shown in Figure 2 the inner end 12 of the ironing board will engage the under side of the bar 9 and the bar 9 will thoroughly brace the 85 ironing board during an ironing operation. The ironing board 10 has its opposite sides adjacent the inner end thereof provided with recesses 13, which recesses, when the ironing board is in vertical position, receive the upper 90 end of the bars 6 as clearly shown in Figures 1 and 3, therefore it will be seen that an ironing board of maximum width may be used as well as a carriage of maximum width, consequently a minimum size 95 cabinet may be imbedded in a wall. The upper ends of the side bars 6 of the carriage have disposed therein spring pressed spherical balls 14, which balls cooperate with recesses 15 in the recessed portions 13 of the 100 ironing board and form detents for holding the ironing board 10 in a vertical position and at the same time in a manner whereby the ironing board 10 may be moved to a horizontal position by simply grasping the 105 free end thereof and pulling the same outwardly. Connected to the upper ends of the side bars 6 at 16 are flexible members 17, which members extend upwardly and over pulleys 18 carried by the sides of the casing 110

1 and terminate in conventional forms of weights 19, which weights are preferably sufficiently heavy to substantially counter-balance the carriage 5 and the ironing board 5 carried thereby, thereby allowing the carriage and ironing board to be positioned at the desired elevation with the minimum amount of power or effort on the part of the operator, and at the same time the weights 10 prevent jamming of the carriage during the movement thereof by imparting an equal pull on the upper end of the carriage at opposite sides thereof.

Pivottally and slidably mounted on the pins 20 carried by the bar 9 are inwardly extending locking levers 21, which levers have their inner ends oppositely bevelled as at 22, whereby when the inner free ends of the levers 21 are forced upwardly by the 20 inner end 12 of the ironing board 10 and the ironing board again moved to vertical position, the levers 21 will be compelled to break downwardly thereby preventing the levers from remaining in the groove 23 in the under side of the bar 9. The pins 20 extend transversely through the bar 9, grooves 23 and elongated apertures 21^a in the levers, therefore it will be seen the levers may move longitudinally. It will be noted that when 30 the levers 21 are forced upwardly at their inner ends, before they are in alinement with each other, said levers will be forced outwardly into engagement with the guide strips 4 incident to the loose connections 20 and the engagement of their inner ends 22, and that the weight of the ironing board will maintain the jamming action above set forth. The pivoted ends 21 preferably engage the guide strips 4.

40 Hingedly connected at 24 to the upper end of the bar 9 is a sleeve board 25, which sleeve 4 is adapted to be moved to a horizontal position as shown in Figure 2 when it is desired to use the same or to a vertical position as shown in Figure 1, when it is not in use. To maintain the sleeve board 25 in a horizontal plane, a hinged supporting leg 26 is provided, which leg is hinged at

27 to the underside of the board 25 and is adapted to engage with its free end the 50 forward side of the bar 9 at the lower edge thereof, thereby supporting the sleeve board. The ironing board 10 prevents downward movement of the leg 26 during an ironing operation on the sleeve board 25. When the 55 sleeve board 25 is in vertical position as shown in Figure 1, it is held in said vertical position by the headed lug 28, which extends through an aperture 29 in the leg 26 adjacent its free end, therefore it will be seen that 60 the sleeve board will be positively held in a vertical position within the casing 1 when not in use.

From the above it will be seen that an ironing board cabinet is provided in which 65 is adjustably mounted a vertically disposed carriage, which carriage is held in various adjusted positions by means of cooperating loosely pivoted locking levers with which the ironing board cooperates when moved to a 70 horizontal position. It will also be seen that means is provided for supporting the sleeve board in a horizontal or vertical position, and said means is formed from a single bracing leg.

The invention having been set forth what is claimed as new and useful is:—

A cabinet ironing board comprising a casing having opposed vertical guide strips, a carriage slidably mounted on said strips, 80 a board hinged adjacent one end of said carriage, means for locking said carriage in different positions comprising a pair of levers pivotally and slidably mounted at their outer ends on opposite edges of the carriage and adapted to be slid into engagement with said strips, the inner ends of said levers being adapted to engage each other, said levers lying in the path of travel of the inner end of the ironing board whereby the board 90 when moved to horizontal position forces said levers into locking engagement with the strips.

In testimony whereof I have signed my name to this specification.

WILLIAM L. McGOWAN.
